UNITED STATES PATENT OFFICE.

GEORGE H. ABRAMS, OF BROOKLYN, NEW YORK, ASSIGNOR OF ONE-FOURTH TO LEAH V. C. NAUL, OF SAME PLACE.

SHIRT.

SPECIFICATION forming part of Letters Patent No. 372,781, dated November 8, 1887.

Application filed April 19, 1887. Serial No. 235,309. (No model.)

To all whom it may concern:

Be it known that I, GEORGE H. ABRAMS, of Brooklyn, Kings county, in the State of New York, have invented a certain new and useful 5 Improvement in Shirts, of which the following is a specification.

The objects of the invention are to provide for raising and lowering the points of attachment of the collar; also to cause the shirt to fit 10 more accurately to the form at the places which are ordinarily somewhat hollowed in front of the shoulders, to avoid bending, or, technically, breaking, the bosom when the wearer sits or otherwise hollows the chest, to provide for enlarging and contracting the neck and adjacent 15 parts of the shirt, so that one size may be adjusted to widely-differing sizes of men, and also to provide passages through which the hands may be conveniently inserted within the 20 shirt at the front. The neckband is provided at the back with a series of button-holes. When the neckband is contracted at the back by shifting the stud into different button-holes to fit a small neck, the peculiar shape of the 25 yokes and adjacent parts favors the change. The neckband is laid out and cut from the plane material in a form approximating the letter V, but with a curve of small radius at the apex, which is at the front, and with the 30 sides curved slightly in the reverse direction. This latter curve provides that the ends or extreme back portions of the neckband are rounded downward. The upper edge of the 35 surplus material is, by the curvature which I give the back portions of the neckband, kept down out of sight. I provide for the variations in size by a double series of button-holes in the neckband on each side of the opening at the back. A stud is inserted through any 40 two of these, according to the size of the neck which is to be matched. I provide on the inside of the neckband at the front, in the apex of the V shape referred to, a flap, which performs important functions. It folds downward 45 on the inside close to the neckband. It is provided with a button-hole, which, when the flap is in that position, coincides with the button-hole in the neckband proper, and the stud at the front of the neckband is inserted through 50 both. In this condition the flap performs no

functions; but when, in consequence of the approach of winter, or for any other reason, the wearer chooses to have his shirt higher at the front, he removes the stud and unfolds the flap, causing it to project above the neckband. 55 He then inserts the stud through the button-hole in the flap alone, and uses it to perform the ordinary functions of the front stud—that is, to hold the front ends of the collar and necktie. In this condition the ordinary button-hole 60 at the front of the neckband remains idle. A similar but longer flap is provided at the back of the neckband on each side of the opening, provided, like the neckband, with a series of button-holes. When it is desired to wear the 65 collar low at the back, these back flaps are folded down below the neckband and the stud is put through both. When, on the contrary, it is desired, as on some occasions of special dress, to wear the collar high at the back, the 70 back flaps are opened upward and the stud is put through them, leaving the button-holes in the neckband unused.

I employ a piece, technically denominated a "yoke," on each shoulder, filling the space 75 between the upper edge in the front, including a portion of the bosom and the back. I make these pieces wider than ordinary yokes, and peculiarly curve the front and back edges. The conditions are such that the front edge of 80 the yoke is farther forward than usual. I correspondingly cut down the front of the shirt, but with a slightly differing curve. This gives an advantage very important under some circumstances. In shifting the front seam of the 85 yoke from its ordinary position on the center of the shoulder to a position considerably forward of that line it avoids subjecting the shoulder to the pressure of the seam. The changed conditions also give a further advantage in allowing the yoke to fit well upon the shoulder and aiding to make the parts lie smoothly, whether the back is let out so as to match a large neck or taken up so as to match a small one. In the act of taking up the shirt by 90 contracting the neckband, in the manner explained, the yoke on each shoulder is gradually shifted over. It is inclined toward the front position when the shirt is adjusted for the largest neck. It is in the central position 95 100

when the shirt is adjusted for a medium neck, and in the back position when the shirt is adjusted for the smallest neck. In the extreme positions, or in any intermediate position, the shirt fits well.

I propose in the manufacture of shirts in the large way to make but two sizes of shirts to fit all sizes of men. They may be known as the "large" and the "small" sizes of shirts. Each is capable of being let out or taken up two inches. I cut the armhole in the body lower than usual at the lower edge, so that there is the same opening as usual for the arm and only the ordinary amount of gathering of the sleeve, notwithstanding the fact that the upper edge of the armhole is somewhat lowered. I provide an opening in the body of the shirt at the front on each side, which is protected or covered by the reinforce, so that it makes a convenient means for the introduction of the hand to adjust the studs or for any other purpose, the junction of the re-enforce with the main body being left open a sufficient space to allow the hand to be thrust up from below.

The accompanying drawings form a part of this specification, and represent what I consider the best means of carrying out the invention.

30 Figure 1 is a front view of the shirt. In this view the flaps at the front and back of the neckband are turned down out of use. Fig. 2 is a front view of a portion. In this view the flaps are turned up in position for use. Fig. 3 is a section on the line $\alpha\alpha$ in Fig. 1. Fig. 4 represents the neckband in the form in which it is cut from the plane material, alone, before being sewed into the shirt. Fig. 5 is a vertical section through the neckband at the back. The condition of the parts corresponds to Fig. 1, but is on a larger scale.

Similar letters of reference indicate corresponding parts in all the figures where they occur.

45 A is the muslin body of the front of a shirt. B is the bosom, which I will assume to be of two or more thicknesses of linen.

C C are re-enforce pieces of muslin reaching down the front each side of the bosom, as usual.

50 D is the back, and E E are the sleeves. These parts may be cut and applied together in the ordinary manner, except in certain points near the top, which will now be described.

55 M is a neckband, which extends around in a single piece and is long enough to encompass the largest neck. The back of the neckband is provided with a double series of button-holes, m, any one of which will receive an ordinary stud. The arrangement allows the neckband to be let out or taken up within wide limits.

P is the stud which is inserted in the front button-hole and performs its usual functions of confining the collar. (Not represented.)

65 Q is the stud which serves at the back, by being inserted in any of the button-holes, m,

to hold the shirt together at the top, and also to hold the collar at the back.

I cut the neckband with a quick curve at the front. It is cut from a plane piece of muslin in a form approximating that of the letter V; but instead of a sharp angle at the apex it is rounded on a small radius, and instead of straight arms they are curved slightly outward, the proper amount being allowed for the seams on each edge. When my neckband is sewed in place on the upper edge of the shirt, it lies nearly in the plane of the bosom at the front, instead of projecting forward, in the ordinary manner, at a considerable angle. The curvature at the sides and back, when applied on the properly-cut yoke, insures that the back ends shall be depressed and concealed whenever the stud Q is inserted through such button-holes m as to contract the neckband to less than its full capacity.

G G are yokes of double muslin, which apply on the shoulders and perform the usual functions, modified and improved by the peculiar form which I give to these parts and to the adjacent parts. I make the yokes wider from the front edge to the back edge than is common. When the neck is let out to its largest size, the yokes extend forward of their ordinary positions. When the neck is contracted by shifting the stud Q successively into different button holes m, so as to fit a smaller and smaller neck, it will usually be the case that the breadth of the shirt at the shoulders should be correspondingly reduced. This is accomplished by my form of the yokes which, as the neck is contracted, shift gradually over from the front to the back of the shoulders. I cut the upper edge of the bosom B and of the front A and re-enforces C so low, or so far forward, that when the neck is the most contracted and the yokes are shifted over backward to their greatest extent the front edge of the yoke is still forward of the central line of the shoulder. This insures that the slight ridge formed by the seam shall never bear disagreeably on the shoulder.

The upper edge of A, B, and C is cut on a curve, the middle of the seam being higher up the shoulder than either end. The adjacent edge of the yoke is also curved. The fact that this seam is always forward of the top of the shoulder allows me to match the shirt to the form at this point very nicely by hollowing it, if desired—that is to say, making the curvature of the top of the front A B C straighter than the adjacent edge of the yoke G. Most forms are a little hollow in the front of the shoulder, and it is ordinarily preferable to make this seam hollow; but, if it is desired in any case, the parts can be cut with exactly the same curve on one as on the other, which will cause the shirt to lie flat, or they can be cut with a greater curvature on the edge of the parts A B C than on the adjacent edge of the yoke G, in which case there will be a fullness along this line adapted to match to a corpulent form.

The seam which joins the back edge of each yoke G to the back D of the shirt shifts forward and backward somewhat, and also changes its inclination as the stud Q is shifted 5 into different button-holes m , so as to take up and let out the neckband.

My shirt is self-adjusting with regard to the width of the shoulders. When the back of the neck is let out to wear a large collar, the man 10 who requires this will usually be correspondingly broad-shouldered. With my shirt the same act of letting out the back of the band to enlarge the neck will also let the yokes move forward and outward and correspondingly 15 broaden the shoulders of the shirt.

T is a flap at the front of the neckband, provided with a button-hole, t , which, when the flap is folded backward and downward within the neckband, coincides in position with the ordinary button-hole. When the stud P is 20 inserted through both the button-holes, laid one upon the other, the shirt is used in the ordinary manner, as above described. When it is desired to make the shirt higher in the 25 neck at the front, the stud is removed and the flap T unfolded and extended upward. Now the stud P is inserted in the button-hole t alone, and stands an inch (more or less) above the other button-hole, thus adding correspondingly to the height of the neck of the shirt. Of course, when the shirt is thus used high-neck, it calls for a smaller collar, which must be provided.

U are corresponding but longer flaps provided near the ends of the neckband. When the shirt is in use, these flaps U come at the back of the neck. They may be each provided with the same number of button-holes as the adjacent portions of the neckband to which 40 they are attached. These flaps U are joined to the neckband along the straight line U'. They lie smoothly against the neckband when they are folded down out of use. They lie smoothly extended when they are unfolded or 45 caused to project upward. Under ordinary conditions these flaps are folded down. In this position they serve the important end of defending the back of the neck of the wearer against the pressure of the stud. With ordinary 50 shirts the pressure of the stud against a small surface on the neck is frequently a source of annoyance. With my shirt one of the flaps U is temporarily unfolded, the stud Q is inserted in the proper hole, m , then the flap U 55 is folded downward, and remains in that position as a protection between the stud and the neck of the wearer. Thus the flap U on the end of the neckband which lies within the other performs a useful function under ordinary 60 conditions.

Another more marked function is performed by each of the flaps U when, in dressing for a ball or for any reason, it is desired to wear the collar higher than usual at the back. In 65 preparing therefor the flaps U are unfolded and extend upward, and the stud Q is inserted through the proper button-holes, u , in the flaps

alone. In this position the stud performs the same function, as before, of holding the back of the neckband together at the proper size, and 70 also of holding the back of the collar, (not shown;) but it holds the collar higher than usual.

Instead of sewing the lower edge of the reinforce pieces C to the adjacent surface of the 75 front body, A, quite across, I leave a space unsewed at C large enough to receive the hand and wrist of the wearer. I cut a slit, a , in the front A on each side of the bosom in the position represented. The hand may be inserted 80 within the bosom to aid in adjusting the studs, or for any other purpose, by thrusting it upward under the lower edge of the re-enforce C, and then inward through the slit a . The arrangement of the apertures insures that the 85 person is covered and protected from sight and from cold.

My yokes E are extended out farther over the shoulders than ordinary yokes. This brings the upper part of the junction of the 90 sleeve with the body lower by an inch (more or less) than with the ordinary shirt. I correspondingly lower the bottom of the junction of the sleeve with the body. Thus I obtain the same size of armhole and the same liberty 95 for movement of the arm in the shirt as with the ordinary construction, but at a lower level. This is an advantage, in allowing the junction of the sleeve to the body to be drawn up by successive contractions of the neck without involving difficulty.

I claim as my invention—

1. In a shirt, the folding flaps T U, provided with button-holes t u , adapted to receive the studs P Q, either in the folded or extended condition, and to attach the collar at correspondingly high or low points, as herein specified.

2. In a shirt having a series of button-holes, m , arranged as shown, the neckband M, having its ends curved downward, so as to be concealed when taken up, in combination with the yokes G, extending forward beyond the center line of the shoulder and the corresponding front parts, B C, and sleeves E, all arranged 115 to serve as herein specified.

3. In a shirt having a main front part, A, and a re-enforce, C, applied as a partial covering therefor, a hand-hole, a , in the main part arranged behind the re-enforce, so as to 120 be covered thereby, in combination with a partial seam or junction of the lower edge of C with A, so as to leave a hand-hole, C', at that point, the two openings a and C' being widely removed, as herein specified.

In testimony whereof I have hereunto set my hand, at New York city, this 14th day of April, 1887, in the presence of two subscribing witnesses.

GEORGE H. ABRAMS.

Correction in Letters Patent No. 372,781.

It is hereby certified that in Letters Patent No. 372,781, granted November 8, 1887, upon the application of George H. Abrams, of Brooklyn, New York, for an improvement in "Shirts," an error appears requiring correction, as follows: On page 1, line 16, in the grant, the grant is made to "George H. Abrams and Leah V. C. Naul, their or assigns," whereas it should have been made to *George H. Abrams and Leah V. C. Naul, their heirs or assigns*, the word "heirs" having been omitted in the original grant; and that the Letters Patent should be read with this correction therein that the same may conform to the record of the case in the Patent Office.

Signed, countersigned, and sealed this 20th day of December, A. D. 1887.

[SEAL.]

D. L. HAWKINS,
Acting Secretary of the Interior.
